UNITED STATES PATENT OFFICE.

JAMES H. BELL, OF HIWASSE, ARKANSAS.

WAGON-BED ATTACHMENT.

1,085,237.

Specification of Letters Patent. Patented Jan. 27, 1914.

Application filed July 21, 1913. Serial No. 780,278.

To all whom it may concern:

Be it known that I, JAMES H. BELL, a citizen of the United States, residing at Hiwassee, in the county of Benton and State of Arkansas, have invented certain new and useful Improvements in Wagon-Bed Attachments, of which the following is a specification, reference being had to the accompanying drawings.

10 This invention relates to new and useful improvements in wagon bed attachments and more particularly to a wagon box fastener and the primary object of the invention is to provide a device of this character which 15 will prevent the loosening of the parts of the wagon bed as the same are jarred in use.

15 A further object of the invention resides in providing a device in connection with the bolster and the side-board which will admit of a yielding action and which will, at the same time, brace said parts, so as to prevent any lateral or longitudinal movement of the same.

20 Still another object of the invention resides in providing a device which is simple and durable in construction, inexpensive to manufacture and one which will be very efficient and useful in operation.

25 With these and other objects in view, the invention consists in the novel features of construction, combination and arrangement of parts as will be hereinafter referred to and more particularly pointed out in the 30 specification and claim.

In the accompanying drawing forming a part of this application, Figure 1 is a fragmentary side elevation of a wagon bed showing my improved device applied to use thereon and showing the bolster in section. Fig. 2 is a vertical section therethrough. Fig. 3 is a similar view as seen on line 3-3, Fig. 1, looking in the direction of the arrow. Fig. 4 is a horizontal section as seen on line 45 4-4, Fig. 1. Fig. 5 is a vertical section as seen on line 5-5, Fig. 1; and Fig. 6 is a fragmentary perspective view showing the complete device applied to use.

In describing my invention, I shall refer 50 to the drawing in which similar reference characters designate corresponding parts throughout the several views and in which 1 indicates a wagon body having the side-board 2 thereon supported above the bolster 3 in the usual manner by means of the

springs 4. Projecting upwardly from the bolster 3, along the outer face of the side-board 2, is a standard 5 which is connected to said side-board in a manner to be herein-after and more particularly described. 60

My invention primarily contemplates the provision of a means which will prevent either a longitudinal or a lateral movement of the wagon body with respect to the bolster in the use of the device and to this end, a 65 shaft 6 is provided and secured to one side face of the bolster 3 by means of the clamp 7. This shaft 6 projects upwardly to a point some distance above the upper edge of the side-board and the upper portion thereof is 70 threaded, as shown at 8.

Secured to the outer face of the side-board 2, to extend longitudinally thereof, at a point adjacent the upper edge of the same, is a plate 9, which has a laterally extending projection 10 formed thereon through which the shaft 6 is loosely disposed and formed. on said plate 9, adjacent the projection 10, are the pair of spaced lugs 11 which 75 slidably receive therebetween the standard 5. 80

A hook-like strap iron 12 is also provided for engagement with the upper end of the side-board, the lower end of said strap iron being bent laterally to form the projection 13, which is also provided with an opening 85 to receive therethrough the shaft 6. This lateral projection 13 which receives the shaft 6 therethrough is designed to rest on the upper face of the projection or keeper 10 of the plate 9 and said hook portion is 90 adapted to be secured to the side-board by the bolt 14. Encircling the shaft 6, so as to rest at its lower end on the projection 13 of the strap 12, is a coil spring 15, and a cotter pin 16 is adapted to be disposed in one of a plurality of openings 17 95 formed in said shaft 6 against which the upper coil of the spring 15 is adapted to contact. Through the medium of a plurality of openings, said cotter pin may obviously be adjusted to adjust the compression of the spring 15 and a nut 18 is applied to the threaded portion of the shaft 6 to contact with said cotter pin, whereby to 100 positively secure the latter in position. 105

From the above description of the construction of my improved device, it will be seen that in a wagon constructed in accordance with my invention and placed in use the body will have a tendency to yield 110

under tension of the spring 4, but will be retarded in its motion by the coil spring 15 of this attachment. It will further be seen that while this attachment permits a vertical movement of the wagon body with respect to the bolster, it will not permit a longitudinal or lateral movement thereof with respect to one another. Thus, any possibility of the parts becoming so loosened from one another as to weaken the wagon in any respect, will be prevented.

From the foregoing it will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to without departing from the spirit or sacrificing any of the principles of the invention.

Having thus described this invention, what is claimed is:—

In a wagon bed attachment, the combination with a bolster and a wagon body yieldingly supported thereon; of a vertical shaft attached to said bolster and projecting on the outer face of the side-board of the body, a member secured to the upper edge of said side-board and having a lateral projection thereon through which said shaft is loosely disposed, a spring member encircling said shaft and resting on said projection, and means engaged with said shaft and the upper end of said spring to secure the latter in position under tension. 25 30 35

In testimony whereof I hereunto affix my signature in the presence of two witnesses.

JAMES H. BELL.
